JASON E. HARRIS, OF HOWARD, KANSAS.

INTAKE VALVE.

Application filed January 4, 1926. Serial No. 79,149.

This invention relates to intake valves for internal combustion engines of that class in which relative changes of angular position between the pistons of the engine and the connecting rods for the pistons, effect, in timed relation to the piston movements, the necessary valve operations for charging, compressing and expanding the gases, and for exhausting the dead gases, and my objects are to simplify and increase the durability of the construction, and increase the efficiency and reliability of operation of such valve mechanisms.

With these objects in view, the invention consists in certain novel and useful features of construction and arrangement of parts, as hereinafter described and claimed; and in order that it may be fully understood reference is to be had to the accompanying drawings, in which:—

Figure 1 is a central vertical section of an internal combustion engine embodying intake valve mechanism embodying my invention, certain conventional parts of the engine being omitted.

Figure 2 is an enlarged central longitudinal section of a part of the engine.

Figure 3 is a cross section on the line III—III of Figure 2.

Figure 4 is a cross section on the line IV—IV of Figure 2.

Figure 5 is a section on the line V—V of Figure 2.

Figure 6 is an edge or side view of the intake valve.

Referring to the drawings in detail, where like reference characters identify corresponding parts in all of the figures, 1 indicates a suitably journaled shaft having a crank 2 enclosed within the crank case 3 of the engine, and 4 indicates cylinders rigid and communicating with the crank case and dispose diametrically with respect to the journaled ends of the crank shaft. Connecting rods 5 extending into the cylinders, are pivotally connected in any suitable or preferred manner to the crank of the crank shaft. At their outer ends the connecting rods have a pivoted relation with the pistons 6 fitting for reciprocative action within the respective cylinders the pivotal connection between the connecting rods and pistons being made by means of cross pivot pins 7.

Each piston has a head 8 set back between its outer end and its respective pivot pin 7, the head being in the form of an annular

flange provided with a circular series of equi-spaced ports 9. The head constitutes a seat for a rotary or oscillatory valve 10 occupying and substantially filling the space outward of the ported head or valve seat, the valve being provided with a step-shaped groove 11 wherein fits a retaining ring 12 screwed into the outer end of the piston to hold the valve properly upon the valve seat. 65

The valve, like the seat, is provided with a circular series of equi-spaced ports 13 for registration with the valve seat ports when the cylinder is being charged with a combustible mixture or gas supplied through 70 and from the rear end of the piston in any suitable manner, not shown, as forming no part of this invention.

The valve is provided centrally with an inwardly-projecting stem 14 having one or 75 more spiral teeth or grooves 15. The stem is provided with a central bore 16, enlarged at its outer end to constitute a pocket 17 and at its inner end to constitute a pocket 18, and the wall of the last-named pocket 80 is provided with a notch 19 for a purpose which hereinafter appears. A piston 20 fits snugly for longitudinal reciprocation in the pocket 17, and has a stem 21 extending through the bore 16 of valve 10, and fulcrumed on the rear end of said stem 21 is a link 22, pivotally connected at its opposite 85 end to a rocker-arm 23 pivoted to a lug 24 projecting from the adjacent end of the respective connecting rod 5. A spring 25 secured to the piston in any suitable manner, 90 exerts outward pressure on the fulcrumed end of the link for the purpose of advancing the piston 20 when no preponderating force or pressure in the cylinder outward 95 of the main piston, prevents such action, it being noted by reference to Figure 2 that when the main or cylinder piston is advancing to compress a charge of gas ahead of it, the pressure thus developed will repress the 100 valve-carried piston 20 and through the link 22, hold the arm 23 swung away from the pivot pin 6. This is true also when the firing action occurs, as at such time the explosive force is sufficient to repress and 105 hold the piston 20 repressed. When the cylinder piston moves inward on its suction stroke or outward on its exhaust stroke, the spring 25 has sufficient power to advance 110 the piston 20 and hence hold the free end of the arm 23 closer to the piston pin 6. The reason for thus positioning the arm 23 as

explained, is to effect oscillation of the main valve through the instrumentality of parts now to be described.

A collar 26 fits slidably on the stem 14 of the main valve and engages with a geared relation the tooth or groove 15 of said stem to turn the latter, and said collar is provided with diametric trunnions 27 pivotally engaging a lever 28 extending across the interior 10 of the cylinder piston and fulcrumed at one end as at 29 upon said piston. The opposite or free end of the lever is connected by a retractile spring 30 to a fixed point, such as a screw 31 secured to the skirt of the piston, and tends to hold the lever in the withdrawn position shown in Figure 2, with the collar 26 at the inner end of the stem 14, it being noted that the lever fits at its free end between guide ribs 32 formed on the piston, to be guided in its swinging movements. Near its fulcrumed end the lever is provided with an opening 33 through which the free end of the arm 23 is adapted to pass under proper change in the angular relation 25 between the connecting rod and the cylinder when the piston 20 is withdrawn. When the piston 20 is advanced under the pressure of spring 25, and shifts outward the fulcrum point of the link, the latter swings the arm 23 inward out of register with the opening 33 of the lever and hence causes the free end of said arm as the change of angular position between the cylinder piston and the connecting rod occurs, as above referred to, 30 to press against the lever inward of said opening 33 and force the lever to swing outwardly and thereby impart outward movement to the collar 26, which outward movement through the engagement of the collar with the spiral tooth or groove of the stem 14 effects a slight rotation or oscillation of the valve to effect registration between the ports 13 thereof and the ports 9 of the valve seat. As this action is completed as the cylinder piston attains its outward limit of movement, gas is permitted to rush through the ports to the head end of the cylinder, and as the piston begins its inward or suction stroke this flow of gas continues. By 35 the time the cylinder has made a half revolution, if the engine is of that type where the crank shaft is stationary, or by the time the crank has made a half revolution if the cylinders are stationary, the piston attains its fully withdrawn position and there is a full charge of gas in the cylinder outward of the cylinder piston, and as the latter begins its outward or compression stroke the gas pressure developed by such action represses the piston 20, and as this occurs the spring 30 withdraws the lever and the latter by withdrawing the collar, reverses the rotation or oscillation of the valve and closes 40 communication between the interior of the piston and the cylinder forward of the piston. When the piston has been fully re-advanced and the compressed charge of gas is exploded by the spark plug and connections, not shown, the pressure developed as herein-after stated, maintains the piston 20 in its 70 repressed position until the cylinder has made another half revolution, and shortly after the ensuing revolution begins to effect the expulsion of the dead gases—the exhaust port, not shown, being now open—the spring 75 25 again re-advances the piston 20 as explained. The piston 20 remains in this position through the ensuing suction stroke, and as the next compression stroke begins said piston 20 is again repressed by the pressure 80 of the gas, to effect the reclosing of the valve. It will thus be seen that the valve control mechanism is entirely automatic and is controlled through a relative change of 85 angular position between the respective pistons and connecting rods. In Figure 1 the four pistons and their equipment, are shown as occupying the four positions which each piston and its equipment occupies during one complete revolution. Assuming that the topmost piston has just completed its exhaust stroke, it will be noted that the right hand piston has made half of its suction stroke, the lower piston has attained its fully withdrawn position and is starting on its compression stroke, and the left hand piston has completed about half of its compression stroke. When the left hand piston attains the topmost position and the explosion occurs, the piston 20 will remain in repressed 90 position for about a half a revolution because the force or power exerted by the explosion and expansion of the gases will overcome the resistance of the spring 25, and shortly after 95 said piston has passed its undermost or half-revolution position and has started on its exhaust stroke with the exhaust port open, the said spring 25 will re-advance the piston 20 and it will remain in such position until it has re-attained its topmost position, 100 at which time the exhaust gases have been 105 expelled, and the valve has again been opened to provide for the recharging of the cylinder with fresh gases upon the ensuing suction stroke. 110

It will be noted by reference to Figures 2 and 3, that to accommodate the advance of piston 20 without corresponding movement of lever 28, the valve stem must not only be notched as at 18, as described, but the collar 26 must have a registering internal notch 26^a into which the link 22 advances as it draws the rocker-arm inward. The notch 26^a is required of course, only on the theory that the pressure developed ahead of the cylinder piston in the exhaust stroke, falls enough to be overborne by the power of spring 20. If such pressure of the exhausting gases preponderates over that of said spring, the piston 20 will not advance at 120 125 130

the time mentioned, and if so, the internal notch 26^a will not be necessary. It is possible however, to so proportion or arrange the parts that the collar shall never interfere with the proper advance of the piston 5 to dispose the rocker-arm in position to advance the lever when it is necessary to open the valve for the suction stroke of the cylinder piston.

10 From the above description, it will be apparent that I have produced an engine embodying the features of advantage set forth as desirable in the statement of the objects of the invention, and it is apparent that the 15 mechanism may be modified in various particulars without departing from the principle of construction and mode of operation involved or from the scope of the appended claims.

20 I claim:

1. The combination of a shaft having a crank, a crank-case enclosing the crank of the shaft, a cylinder rigid and communicating at its inner end with the crank-case, a 25 reciprocating piston in the cylinder and a connecting rod pivotally connecting the piston and said crank, the piston having a ported head constituting a valve seat; and oscillatory valve upon said seat and provided with a chamber in its face and a port to register at times, with the port of the 30 valve seat to establish communication between the interior of the piston and the head end of the cylinder, a piston in said chamber, means tending to advance said last-named piston, a link bearing a fulcrumed 35 relation to the last named piston, a rocker-arm pivotally connected to the connecting rod and to said link, and means for oscillating the valve under pressure applied by the 40 rocker-arm incident to a change in the angular relation between the cylinder and the connecting rod when the said valve-carried piston is advanced.

45 2. The combination of a shaft having a crank, a crank-case enclosing the crank of the shaft, a cylinder rigid and communicating at the inner end with the crank-case, a reciprocating piston in the cylinder and a 50 connecting rod pivotally connecting the piston and said crank, the piston having a ported head constituting a valve seat; an oscillatory valve upon said seat and provided with a chamber in its face and a port to register at time, with the port of the 55 valve seat to establish communication between the interior of the piston and the head end of the cylinder, a piston in said chamber, means tending to advance said last-named piston, a link bearing a fulcrumed 60 relation to the last named piston, a rocker-arm pivotally connected to the connecting rod and to said link, means for oscillating the valve under pressure applied 65 by the rocker-arm incident to a change in

the angular relation between the cylinder and the connecting rod when the said valve-carried piston is advanced, and means for effecting reverse action of the valve-oscillating means to reverse the oscillation of the 70 valve as said connecting rod reverses its angular relation with respect to the cylinder piston.

3. The combination of a shaft having a crank, a crank-case enclosing the crank of the shaft, a cylinder rigid and communicating at its inner end with the crank-case, a reciprocating piston in the cylinder and a connecting rod pivotally connecting the piston and said crank, the piston having a 75 ported head constituting a valve seat; an oscillatory valve upon said seat and provided with a chamber in its face and a port to register at times, with the port of the valve seat to establish communication between the interior of the piston and the head end of the cylinder, a piston in said chamber, means tending to advance said last-named piston, a link bearing a fulcrumed 80 relation to the last named piston, a rocker-arm pivotally connected to the connecting rod and to said link, a lever within and fulcrumed on the cylinder piston and provided with an opening, a spring tending to hold said lever swung toward the inner end 85 of the cylinder with its opening in position to receive the free end of the said arm as the latter is advanced by a change in the angular relation between the cylinder piston and the connecting rod when the valve-carried piston is retracted, and a gearing connection between said lever and the valve for holding the latter against accidental oscillation when the lever is at rest.

4. The combination of a shaft having a crank, a crank-case enclosing the crank of the shaft, a cylinder rigid and communicating at its inner end with the crank-case, a reciprocating piston in the cylinder and a connecting rod pivotally connecting the piston and said crank, the piston having a 100 ported head constituting a valve seat; an oscillatory valve upon said seat and provided with a port to register at times, with the port of the valve seat to establish communication between the interior of the piston and the head end of the cylinder, and provided with a rearwardly projecting stem and a bore enlarged at its front end to form a chamber, a collar slidable longitudinally upon said stem and bearing a geared relation thereto to turn the valve to open position or to closed position accordingly as the collar is moved outward or inward, a lever 105 pivoted to said collar and fulcrumed at one end on the cylinder piston, a spring connected to the lever and normally holding the same retracted inwardly with respect to the cylinder, a piston in the said chamber of the valve, provided with an inwardly-pro- 110

jecting stem, a link fulcrumed upon the inner end of said stem, a spring applying pressure to advance the valve-carried piston, a rocker-arm pivoted to the connecting rod and to said link, and adapted accordingly as the valve-carried piston is advanced or retracted, to apply or not apply advancing

pressure on said lever as the connecting rod in changing its angular relation to the cylinder piston, advances said arm. ¹⁰

In witness whereof I hereunto affix my signature.

JASON E. HARRIS.
